MULTIPLE ELECTRIC OUTLET BAR

Robert D. Kahn, Rockville Centre, N.Y., assignor to
Fedtro, Inc., Rockville Centre, N.Y., a corporation of
New York

Filed Apr. 16, 1969, Ser. No. 16,777

Term of patent 14 years

Int. Cl. D13—03

U.S. Cl. D26—1

FIG. 1 is a three-quartered front perspective view of the multiple electric outlet bar;

FIG. 2 is a top plan view thereof;

FIG. 3 is a front elevational view thereof;

FIG. 4 is a left side elevational view thereof; and

FIG. 5 is a right side elevational view thereof.

The broken lines are for illustrative purposes only.

I claim:

The ornamental design for a multiple electric outlet bar, as shown and described.
